UNITED STATES PATENT OFFICE.

VERNON DURBIN, OF BROOKLINE, MASSACHUSETTS, ASSIGNOR TO HOLTZER-CABOT ELECTRIC COMPANY, OF BROOKLINE, MASSACHUSETTS, A CORPORATION OF MASSACHUSETTS.

TRANSMITTER FOR SELECTIVE SIGNALING SYSTEMS.

1,053,584.

Specification of Letters Patent. Patented Feb. 18, 1913.

Original application filed May 16, 1910, Serial No. 561,645. Divided and this application filed October 7, 1910. Serial No. 585,808.

To all whom it may concern:

Be it known that I, VERNON DURBIN, a citizen of the United States, and a resident of Brookline, in the county of Norfolk and State of Massachusetts, have invented a new and useful Improvement in Transmitters for Selective Signaling Systems, of which the following is a specification.

My invention relates to transmitters for selective signaling systems adapted for use more especially in train-despatching telephone-systems.

The primary object of my invention is to provide a transmitter whereby an operator can send a signal to any one of a number of receiving stations to the exclusion of the others.

A secondary object is to provide means whereby the rotating parts at the several receiving stations and at the transmitting station are automatically synchronized or kept in step during the usual operation of the apparatus without any special act of the operator, although said rotating parts may, if desired, be all set to zero position or synchronized by a special operation as herein-after more fully described.

In the drawings which accompany and form a part of this specification, I have shown one arrangement of apparatus and circuits whereby the foregoing objects may be effected; although it will be understood that many modifications may be made by those skilled in the art both in the apparatus and in the circuit arrangements without departing from the principle of my invention.

In the drawings, Figure 1 is a diagram representing a receiving station; Fig. 2 is an elevation of a portion of the apparatus shown in Fig. 1; Fig. 3 is a diagram of one form of transmitting system that may be employed with the receiving system illustrated in Fig. 1; Fig. 4 is an elevation of a portion of the apparatus at the transmitting station; Fig. 5 is a plan view of the apparatus shown in Fig. 4, and Fig. 6 is a diagram showing the circuits of a complete system.

In order to more fully disclose my invention, I have shown in Figs. 1 and 2, one form of receiving apparatus that may be employed in connection with my improved

transmitter. In Fig. 1 a polarized magnet is bridged across the line L, L, between the points a, b, and is arranged to actuate the armature 2 which is pivoted at 2' and carries the escapement 3. The shaft 5 which may be driven by any suitable motor, such as the spring motor 6, carries the escapement wheel 4 with which the escapement 3 co-operates, the toothed wheel 7, and the contact arm 14. The escapement wheel has one more tooth than the wheel 7, one of the teeth of the latter having been omitted, as shown at 9, at a point diametrically opposite the stop-arm 8 which is carried by said wheel. The armature 10 which is pivoted at 10' and provided with the yoke 10'', is arranged to be oscillated by the polarized magnet 15 and carries at one end of its yoke a wheel-arresting device such as the pest 11, and at the other a wheel-locking device, such as the tooth 12 arranged to co-operate with the notches between the teeth 7 of the wheel 7. The contact point 13 may also be carried by and insulated from the yoke and is arranged to co-operate with the contact arm 14.

The contact arm 14 is connected with one side of the line at the point c in any suitable manner, as for example by the brush 16 which makes contact with the shaft 5 as shown in the present case, although it will be understood in practice that the frame 85 which carries the said shaft will be conductively connected to one side of the line, as at the point c. The circuit containing the receiving station signaling apparatus may be connected between the other side of the line as at the point d and the contact point 13. In Fig. 1 said signal apparatus is shown as a polarized bell connected between the point d and the contact point 13 through the condenser 18.

The operation of the receiving system is as follows: Each receiving station will be provided with apparatus identical with that shown in Fig. 1 and the contact arms 14 will be arranged in successive positions around the circumference of the toothed wheel 7 so that each arm is arranged opposite a different one of the notches, that is to say, station No. 1, for example, may have its arm 14 arranged opposite the first notch & from the double notch 9, station No. 2 may

have its arm 14 arranged opposite the next notch *y* and station No. 3 may have its arm 14 arranged opposite the next notch *z*, etc., no station having its arm 14 arranged opposite the double notch 9. If the central station desires to call one of the receiving stations, a series of current pulsations equal in number to the number of the station to be called will be sent over the line and will 5 actuate the polarized magnet 1 so as to oscillate the escapement and permit a step by step rotation of the wheel 7 until the arm 14, rigidly carried by the shaft to which said wheel is connected, comes opposite the contact point 13, whereupon a pulsation of current opposite in polarity to those which effected the rotation of the wheel 7, is transmitted to energize the magnet 15 thereby bringing the point 13 into contact with the 10 arm 14 to close the circuit between the points *c* and *d* and actuate the local signaling apparatus 19, and placing the tooth 12 in one of the notches to lock the wheel against further rotation. Assuming that 15 the armature 2 is in the position shown, a current impulse of one polarity will cause the magnet 1 to attract the righthand end of the armature, and at the same time charge the condenser 17. Simultaneously, said 20 impulse will energize the polarized magnet 15 and cause the armature 10 to take the position shown, the contact point 13 being out of contact with the arm 14 and the post 11 being in its wheel-arresting position in 25 the path of the stop-arm 8. As soon as said impulse ceases, the condenser discharges through the magnets 1 and 15, such discharge through the magnet 1 being opposite to the original direction of current flowing 30 therethrough, so that the lefthand side of the armature is again attracted. However, the direction of the condenser discharge through the magnet 15 is the same as that of the original current flow therethrough, 35 so that the position of the armature 10 is not altered. The solid arrows in Fig. 1 indicate the direction of flow of said current impulse through the magnets and the dotted arrows the direction of the condenser discharge 40 therethrough. The signal impulse causes the wheel 7 to rotate past the tooth 12 to the extent of one notch, said tooth always being opposite a notch when the magnet is deenergized, or in other words, 45 when the armature 2 is in the position shown. Thus, if the train-despatcher desires to call the station numbered five, he will transmit five current impulses of a given polarity, (assuming of course that 50 each wheel has been "set to zero") so as to bring the contact arm 14 at station 5 but at no other station, opposite the tooth 12 and contact point 13. He will then 55 transmit one current impulse of the opposite polarity with the result that the cur-

rent flowing through the magnet 1 will not cause the armature 2 to be moved because this reverse impulse is in the same direction as the original condenser discharge, which as above explained, caused the armature to 60 take the position shown. This pulsation of reverse current, however, flowing through the magnet 15, will cause the armature 10 to move to the left so that the tooth 12 engages a notch in the wheel 7 and locks the 65 same against further rotation, and the contact point 13 closes on the contact arm 14. The operator may now transmit a number of current impulses of said opposite polarity for the purpose of actuating the polarized bell 19 or other local signal device. It will be understood of course that each 70 magnet 15 at all the stations will operate the armatures 10 in the manner above set forth and that the teeth 12 will arrest the 75 further rotation of all the wheels 7, but inasmuch as the contact arms 14 are arranged as above described, none of the local signaling apparatus will be actuated at the other stations. Upon the sending of an impulse 80 or impulses in the original direction, the armature 10 is again moved to the position shown in Fig. 1 by the energization of the magnet 15, the tooth 12 is thereby disengaged from its locking position, and the 85 armature 2 is again oscillated in the manner set forth.

To set the toothed wheel 7 at zero with the center of the notch 9 opposite the tooth 12 and the stop-arm 8 against the post 11, the operator at the transmitting station will 90 send over the line pulsations in the original direction (shown by the solid arrow) equal in number to the number of teeth on the wheel 7, thereby bringing every stop-arm 95 against its coöperating stop-post. He will then send over the line one pulsation in the direction of the solid feathered arrows, whereupon each stop-arm will be released 100 in the following manner: Such reversed pulsation will pass through the magnets 1 in the direction of the solid feathered arrow when the armature is in the position shown in Fig. 1, so that said armature will not be 105 oscillated, and said pulsation will pass through the magnet 15 in the direction of the solid feathered arrow so that the armature 10 will be attracted to the left, thereby moving the post 11 to its releasing position out of the path of the stop-arm and the tooth 12 into the notch 9. When said reversed pulsation ceases, the condenser 17 discharges in the direction of the dotted feathered arrow (which direction is the same as 110 the original current impulse) so that the armature 2 is oscillated and the wheel 7 stepped around a space equal to one notch, thereby bringing the stop-arm directly opposite the post, this movement of the wheel 115 being permitted by the double notch 9. The 120

condenser discharge passes through the magnet 15 in the same direction as the reversed impulse, so that the armature 10 is not moved back to the right. An impulse is thus sent over the line in the original direction, oscillating the armature 2 and throwing the armature 10 over to the right in the position shown in Fig. 1. The cessation of this impulse will then cause the wheel to move half a notch farther, so that one pulsation will now cause the contact arm 14 of station 1 to come opposite the contact point 13, two pulsations will cause said arm to come opposite said point at station 2, and so on.

The transmitting station will be provided with an apparatus similar to that shown in Fig. 1, but provided with means for automatically sending over the line any desired number of impulses of a given polarity followed by one impulse of the opposite polarity, such reversed current impulse being for the purpose of placing each post 11 in its releasing position and enabling each stop arm to pass the same. For instance, with the apparatus set in the position shown in Fig. 1, in which the arm 14 of station 46 is opposite the contact point 13, it will be obvious that four pulsations of current will cause all the stop-arms 8 to come in contact with their respective posts, so that were a reversed current impulse not sent at the end of four direct current impulses, the motion of all the wheels would be arrested. The sending of this reversed current impulse will not actuate any local signal apparatus, for the reason, as above explained, that no contact arm 14 is located opposite the notch 9. Thus if any wheel or wheels is out of step with the rest, the ordinary operation of the apparatus for signaling will automatically effect the synchronization of the step-by-step rotating parts once during every revolution and a small fraction thereof,—in other words, the stop-arm 8 at the transmitting station cannot pass the post 11 at said station twice successively without effecting the complete synchronization or the setting to zero of all the wheels 7.

In apparatus of this kind where a number of widely separated step-by-step mechanisms are employed, it is of course necessary to employ synchronizers, and so far as I am aware, the synchronization of such parts has heretofore always been effected by a special apparatus requiring a special operation on the part of an attendant. It will therefore be seen that the automatic synchronization of the several toothed wheels forms a salient feature of my invention.

The present system is intended for use over a relatively long line, about two hundred miles in length comprising a number of receiving stations (shown in the present instance as forty-eight) and therefore I prefer

to employ polarized magnets in all instances because of the well known sensitiveness of such apparatus.

In the commercial use of the receiving system shown in Fig. 1, it is desirable for obvious reasons that means be employed whereby the various operations heretofore described shall be automatically performed.

In Fig. 3 I have illustrated diagrammatically one arrangement of the automatic transmitting apparatus which constitutes the subject matter of the present invention, although it will be understood of course that said transmitting apparatus is not limited to use in connection with the receiving apparatus above described.

In Fig. 3, 33 represents a suitable source of electric energy connected normally through the hold-back magnet 34, contact 33, and armature 52, so that the armatures 36, 37 of the vibrator magnet 35 which by their spring-supports 36', 37' are held away from their coöperating contacts 40, 41 are attracted and held back against vibration until the magnet 34 is deenergized. 56 represents a manually-operated contact member or plunger provided with an insulated head 57 and carrying the contact 58 which is connected to one side of the battery at *j*. It will be understood that the transmitting apparatus will be provided with as many plungers as there are receiving stations, although for convenience only one has been shown in Fig. 3. When the plunger is pushed inward, the contact piece 58 engages 95 the spring contact member 59, thereby closing the circuit of the vibrator magnet 35 through the battery by way of the point *f*, through the spring 38, contact 39, windings of the magnet 35, spring 59, contact piece 100 58, point *j*, thence back to the battery, and also closing the circuit of the starting magnet 51 through the battery by way of the point *g*, windings of the magnet 51, spring 59, contact piece 58, point *j*, thence back to 105 the battery. The energization of the starting magnet closes the circuit of the condenser 61, bridged across the line *L*, *L* between the points *k* and *l*, through the armature 54 and contact 55, and at the same time opens the circuit of the hold-back magnet 34 between the armature 52 and its coöperating contact 53. The armatures 36 and 37, which may be mechanically connected, are now set in vibration and pulsating currents are sent over the line by way of contact 40, armature 43 of the receiving relay 42, contact 50, against which said armature normally is held, impedance coils 60, to the line, and back through the impedance coils 60', contact 48, against which the armature 44 normally is held, contact 41, and armature 36, the circuit being completed through the battery by way of the point *h* and thence to the armature 37 of the 120 130

vibrator magnet and contact 40 by way of the point *f*.

The shaft 5' at the transmitting station carries apparatus identical, except for the omission of the contact point 13, with that carried by the shaft 5 at each receiving station, and is governed by a magnetically operated escapement in the same way as the receiving station apparatus, the control magnets for said escapement being connected across the line. The contact arm 14' at the transmitting station is arranged to make contact with, and to have its motion arrested by, a plunger 56 when the same is completely depressed, and the post 11' carried by a yoke identical with the receiving station yoke 10' is connected to one side of the battery at the point *i*. It will be understood of course that at the transmitting station the contact point 13 is removed from the yoke and there is no apparatus corresponding to the signaling device 19.

When any one of the plungers 57 (see Fig. 5) is depressed sufficiently to bring the contact piece 58 into engagement with the spring 59, but not sufficiently to cause the end of the plunger to engage the contact arm 14', the pulsating currents which are sent out over the line in the direction of the solid arrow shown in Fig. 1, cause all the wheels 7 to rotate until the movement thereof is arrested by the stop-arms 8 coming into contact with their respective posts 11. As soon as the stop arm 8' at the transmitting station engages the post 11', the circuit through the reversing relay is closed through the battery by way of points *e*, *f*, windings of magnet 42, point *m*, shaft 5', arm 8', post 11', and thence back to the battery by way of the point *i*. The energization of the magnet 42 causes the armatures 43, 44 to be thrown over to current-reversing position against the contacts 47, 49, respectively, thereby sending one pulsation of reversed current over the line, which actuates all the magnets 15 including the one at the transmitting station, so that, as above described in connection with Fig. 1, each post is moved to the left to its releasing position so as to permit the stop-arms to move past the posts.

After the contact between 8' and 11' is broken, the reversing relay is held in current-reversing position by the by-path *m* 46 45 41 36 *h*, and is not deenergized by the opening of the contact between the post 41 and the armature 36 until shortly after the breaking of the contact between 8' and 11'. The magnets 1 of the step-by-step apparatus which carry the arms 8, 8' are energized by intermittent currents. When the armature 37 makes contact with the post 40, a current impulse is sent to line and causes the armature 2 to take a certain position. When the armature 37 is in the position shown in Fig.

3, the flow of current to the line is interrupted and the discharge of the condenser 17 causes the armature 2 to take its other position. The armature 36 vibrates synchronously with armature 37 and the apparatus is so arranged that when armature 37 is out of contact with post 40, the arm 8' is in contact with post 11'. As the armatures 36 and 37 vibrate synchronously it follows that when armature 37 is out of contact with post 40, armature 36 is out of contact with post 41. The next impulse sent to line by armature 37 contacting with post 40 will cause arm 8' to leave the post 11', and inasmuch as the armatures 36 and 37 vibrate synchronously, it follows that the armature 36 is in contact with the post 41 when the arm 8' leaves the post 11'. Therefore the reversing relay is held in current-reversing position by said by-path and is not deenergized by the opening of said by-path between the armature 36 and post 41 until shortly after the breaking of the contact between arm 8' and post 11', so that a complete current impulse is transmitted. (If the circuit of the reversing relay were broken instantaneously by 8' passing 11', the contacts between 43, 47 and 44, 49 would not remain closed long enough to permit a complete pulsation of reversed current to pass to the line.) When the reversing relay has been deenergized, current pulsations in the original direction are again sent over the line, thereby causing the wheels 7 to continue their step-by-step rotation. To set all the wheels at zero, the transmitting operator will therefore depress any one of the plungers 56 until the contact arm 8' has twice passed the post 11' and the wheel 7 at his station has made a revolution and a fraction thereof. In view of what has heretofore been said in regard to automatic synchronization, it will be understood that the special synchronizing operation just described will be but rarely necessary.

To call any given receiving station, the operator depresses the corresponding plunger 56 to its full extent, the contact piece 58 passing over, but still remaining in contact with, the spring 59, so that without breaking contact with the spring 59, its inner end is in the path of the arm 14'. As soon as the motion of the wheel 7 at the transmitting station is arrested by the arm 14' striking the end of the plunger 56, the circuit of the reversing relay is closed through the battery by way of the points *e*, *f*, winding of the magnet 42, point *m*, shaft 5', arm 14', plunger 56, point *j*, and thence back to the battery whereupon reversed current pulsations are sent over the line until the plunger is withdrawn, with the result that every armature 10 at every receiving station is thrown over to the left (from the position shown in Fig. 1) and the contact 130

point 13 at the particular station called is brought against the contact arm 14 at said station, thereby actuating the local signal apparatus in the manner heretofore described. It will be noted that when the wheels 7 are all in step, all the stop-arms 8 will come against their respective posts 11 at the same instant, and that the reversed current impulse sent out as above described 10 by the contact formed between 8' and 11' will move each post out of the path of its coöperating stop-arm, so that the movement of the wheels is never more than momentarily arrested, but in cases where a wheel 15 is out of step with the other wheels, the movement of the wheel in question is arrested one or more times until it is brought into step with the others.

When the reversing relay is energized and 20 the armature 44 thrown over against its contact point 49, the spring contact 45 is brought against the post 46, thereby closing the by-path above referred to which completes the circuit of the reversing relay by 25 way of the contact 41 and armature 36, and keeps said relay energized for the exceedingly short interval of time between the breaking of the contact of the plunger with the arm 14' and the breaking of the contact 30 of the contact piece 58 with the spring 59, so that every time a plunger is withdrawn, the last impulse sent over the line will be a reversed current impulse and the armature 2 at every station will be in the position shown 35 at Fig. 1. If this by-path were not formed, the reversing relay would be deenergized as soon as the plunger broke contact with the arm 14, and a partial direct impulse would be transmitted to the line before the contact 40 piece 58 was withdrawn from engagement with the spring 59.

It will be noted that by means of the transmitting apparatus shown in Fig. 3, the step-by-step rotating parts of all the 45 stations automatically are synchronized during the operation of the apparatus in its intended manner without requiring any special synchronizing operation on the part of the operator.

50 The function of the condenser 61, bridged across the line by the energization of the starting relay 51, is merely the usual function of such condenser to prevent sparking at the contacts between 37 and 40, and 55 38 and 39. When a station has been called and the plunger withdrawn, the magnet 51 is deenergized and the condenser disconnected so as not to reduce the efficiency of the line for the transmission of telephone 60 currents. The impedance coils 60, 61', which may be employed, perform the usual function of "smoothing out" the pulsations.

In Figs. 4 and 5, I have shown the step-by-step mechanism for the transmitting station which has been indicated diagram-

matically in Fig. 3, it being understood of course that there will be one plunger 56 for every receiving station associated with the system. With the exception of the contact point 13 and the connection of the stop post 11' to the battery at the point *i*, the step-by-step mechanism at the transmitting station is identical with those at the receiving station.

70 In Fig. 6 I have shown the circuits of a 75 complete system including the transmitting station and two receiving stations bridged across the main line, the same reference characters as in the other figures being employed so that Fig. 6 will readily be understood from the detailed description of the other figures.

This application is a division of my application Serial No. 361,645, filed May 16, 1910.

80 Although I have described my invention with some particularity as applied to a telephone system, it will readily be understood that it is not limited to such application and that it may be applied to any system 90 where in the selective control of rotating members by a distantly-located transmitter is required.

I claim:

1. In a selective signaling system, a transmitting apparatus comprising a source of pulsating current, a rotatable contact member, means controlled by current impulses of a given polarity for imparting a step-by-step rotation thereto, arresting-means for 100 stopping the rotation of said member at a given point, and means controlled by said arresting-means for causing said apparatus to transmit a current impulse of the opposite polarity.

105 2. In a selective signaling system, a transmitting apparatus comprising a source of pulsating current, a rotatable contact member, means controlled by current impulses of a given polarity for imparting a step-by-step rotation thereto, arresting-means for stopping the rotation of said member at a given point, means controlled by said arresting-means for causing said apparatus to transmit a current impulse of the opposite 115 polarity and a magnetic control device for said arresting-means, said magnetic control device being constructed and arranged to be actuated by said current impulse of opposite polarity for moving said arresting-means to releasing-position.

120 3. In a selective signaling system, a transmitting apparatus comprising a source of pulsating current, a rotatable contact member, means controlled by current impulses of a given polarity for imparting a step-by-step rotation thereto, a reversing relay associated with said source of pulsating current, arresting-means for stopping the rotation of said member at a given point, and 130

means controlled by said arresting-means for causing said reversing relay to reverse the polarity of the current impulses transmitted.

5. In a selective signaling system, a transmitting apparatus comprising a source of pulsating current, a rotatable contact member, means controlled by current impulses of a given polarity for imparting a step-by-step rotation thereto, a reversing relay associated with said source of pulsating current, arresting-means for stopping the rotation of said member at a given point, means controlled by said arresting-means for causing said reversing relay to reverse the polarity of the current impulses transmitted, and a magnetic control device for said arresting-means, said magnetic control device being constructed and arranged to be actuated by a current impulse of the opposite polarity for moving said arresting-means to releasing position.

5. In a selective signaling system, a transmitting apparatus comprising a source of pulsating current, a rotatable contact member, means controlled by current impulses of a given polarity for imparting a step-by-step rotation thereto, a reversing relay associated with said source of pulsating current, arresting-means for stopping the rotation of said member at a given point, means controlled by said arresting-means for actuating said reversing relay, and means maintaining said reversing relay in current-reversing position after said arresting-means has assumed its releasing-position and until a complete impulse of said opposite polarity has been transmitted.

6. In a selective signaling system, a transmitting apparatus comprising a source of direct current, an electromagnetic current-interrupter associated therewith, a rotatable contact member, means controlled by current impulses of a given polarity for imparting step-by-step rotation to said contact member, a reversing switch arranged to reverse the polarity of the transmitted impulses, a magnetic control device for said reversing switch, and means associated with said rotatable contact member for controlling said magnetic control device.

7. In a selective signaling system, a transmitting apparatus comprising a source of direct current, an electromagnetic current-interrupter associated therewith, a rotatable contact member, means controlled by current impulses of a given polarity for imparting step-by-step rotation to said contact member, a reversing switch arranged to reverse the polarity of the transmitted impulses, a magnetic control device for said reversing switch, means associated with said rotatable contact member for controlling said magnetic control device, and means independent of said rotatable contact member for main-

taining said reversing switch in current-reversing position until a complete impulse of opposite polarity has been transmitted.

8. In a selective signaling system, a transmitting apparatus comprising a source of direct current, an electromagnetic current-interrupter associated therewith, a rotatable contact member, means controlled by current impulses of a given polarity for imparting step-by-step rotation to said contact member, a reversing switch arranged to reverse the polarity of the transmitted impulses, a magnetic control device for said reversing switch, means associated with said rotatable contact member for controlling said magnetic control device, a by-path independent of said rotatable contact member, and a supplemental contact for said reversing switch arranged, when said switch is in current reversing position, to close the circuit of said magnetic control device through said by-path.

9. In a selective signaling system, a transmitting apparatus comprising a source of direct current, an electromagnetic current-interrupter associated therewith, a rotatable contact member, means controlled by current impulses of a given polarity for imparting step-by-step rotation to said contact member, a reversing switch arranged to reverse the polarity of the transmitted impulses, a magnetic control device for said reversing switch, means associated with said rotatable contact member for controlling said magnetic control device, a by-path independent of said rotatable contact member, a supplemental contact for said reversing switch arranged, when said switch is in current reversing position, to close the circuit of said magnetic control device through said by-path and a contact arranged to be opened by said current-interrupter for opening said by-path and thereby deenergizing said magnetic control device.

10. In a selective signaling system, a transmitting apparatus comprising a source of pulsating current, a rotatable contact member, means controlled by current impulses of a given polarity for imparting a step-by-step rotation thereto, a reversing relay associated with said source of pulsating current, a manually-operated contact member adapted to coöperate with said rotatable contact member, and a circuit through said reversing relay arranged to be closed by said contact members and thereby cause current impulses of the opposite polarity to be transmitted.

11. In a selective signaling system, a transmitting apparatus comprising a source of direct current, an electromagnetic current-interrupter associated therewith, a rotatable contact member, means controlled by current impulses of a given polarity for imparting a step-by-step rotation to said contact mem-

- ber, a reversing switch arranged to reverse the polarity of the transmitted impulses, a magnetic control device for said reversing switch, a manually-operated contact member adapted to coöperate with said rotatable contact member, and a circuit through said magnetic control device arranged to be closed by said contact members and thereby cause current impulses of the opposite polarity to be transmitted.
12. In a selective signaling system, a transmitting apparatus comprising a source of direct current, an electromagnetic current-interrupter associated therewith, a rotatable contact member, means controlled by current impulses of a given polarity for imparting a step-by-step rotation to said contact member, a manually-operated contact member adapted to coöperate with said rotatable contact member, a circuit through said current-interrupter, and means whereby said circuit is closed by said manually-operated contact member before the coöperation of the latter with said rotatable contact member.
13. In a selective signaling system, a transmitting apparatus comprising a source of direct current, an electromagnetic current-interrupter associated therewith, a rotatable contact member, means controlled by current impulses of a given polarity for imparting step-by-step rotation to said contact member, a normally energized holding-magnet for said current-interrupter, a manually-operated contact member adapted to coöperate with said rotatable contact member, and means controlled by said manually-operated contact member for deenergizing said holding-magnet before the coöperation of said manually-operated contact member with said rotatable contact member.
14. In a selective signaling system, a transmitting apparatus comprising a source of direct current, an electromagnetic current-interrupter associated therewith, a rotatable contact member, means controlled by current impulses of a given polarity for imparting a step-by-step rotation to said contact member, a holding-magnet for said current-interrupter, a normally deenergized starting-magnet, an armature for said starting-magnet, a circuit including said source of direct current and holding-magnet normally closed by the armature of said starting-magnet, a manually-operated contact member adapted to coöperate with said rotatable contact member, and means controlled by said manually-operated contact member for energizing said starting-magnet and thereby breaking the circuit of said holding-magnet.
15. In a selective signaling system, a transmitting apparatus comprising a source of direct current, an electromagnet current-interrupter associated therewith, a rotatable contact member, means controlled by current impulses of a given polarity for imparting a step-by-step rotation to said contact member, a manually-operated contact member adapted to coöperate with said rotatable contact member, a condenser and means controlled by said manually-operated contact member for connecting said condenser across the contacts of said current-interrupter.
16. In a selective signaling system, a transmitting apparatus comprising a source of pulsating current, a rotatable contact member, means controlled by current impulses of a given polarity for imparting a step-by-step rotation thereto, a reversing relay, a plurality of manually-operated contact members each adapted to coöperate with said rotatable contact member, and a circuit through said reversing relay adapted to be closed by the coöperation of said rotatable contact member with any one of said manually-operated contact members and thereby cause current impulses of the opposite polarity to be transmitted.
17. In a selective signaling system, a transmitting apparatus comprising a source of direct current, an electromagnetic current-interrupter associated therewith, a rotatable contact member, means controlled by current impulses for imparting step-by-step rotation to said contact member, a reversing mechanism arranged to reverse the polarity of the transmitted impulses, a magnetic control device for said reversing mechanism, and means associated with said rotatable contact member for controlling said magnetic control device.
- In testimony whereof, I have hereunto subscribed my name this 21st day of Sept. 1910.
- VERNON DURBIN.
- Witnesses:
- WALTER F. TAYLOR,
ALFRED P. WATERMAN.
